THREAD CONTROL FOR WEFT
REPLENISHING LOOMSRichard G. Turner, Worcester, Mass., assignor to
Crompton & Knowles Loom Works, Worcester,
Mass., a corporation of Massachusetts

Application April 27, 1950, Serial No. 158,357

11 Claims. (Cl. 139—257)

1

This invention relates to improvements in control means for the thread of the incoming bobbin on weft replenishing looms and it is the general object of the invention to provide simple means for trapping the thread to hold it out of the path of the shuttle.

In weft replenishing looms the bobbin transferred into the depleted shuttle ordinarily has a thread or weft end attached to some form of thread holder so that as the shuttle is picked a partial self-threading operation will occur. On the beat-up of the loom next following replenishing this thread is beaten into the fell of the cloth and extends from the selvage to the thread holder where it will be held until cut by a selvage cutter.

A form of weft replenishing mechanism adaptable more particularly for multicolor work employs a shuttle position detector pivoted to the reserve bobbin magazine at a point above the lay when the latter is on front center. The lower end of the detector is made with a nose or the like normally forward of the shuttle when the lay is on front center. When the magazine is set for a weft replenishing operation the shuttle detector moves rearwardly so that its nose will be struck by the shuttle should the latter be mislaced for the purpose of revoking the previously called transfer and prevent the insertion of a reserve bobbin into the misplaced shuttle. It has been customary in the past to form the nose or head of this shuttle feeler with a forwardly and upwardly extending hook for engagement with the previously mentioned thread of the incoming bobbin, but because of vibration in the loom and the nature of some threads it is difficult to keep the thread in its proper position in front of the hook.

The shuttle feeler is usually provided with a cutter for the thread of the outgoing bobbin and also a clamp to hold this thread. The clamp holds this second thread near the bottom of the aforesaid nose or head until it is cut at the selvage. If the first mentioned thread is not trapped and held separated from the second thread it may become entangled with the latter thread and interfere with its removal when cut.

It is an important object of the present invention to provide simple means which will trap the thread of the incoming bobbin in a zone in front of the hook on the nose and above the thread of the outgoing bobbin clamped at the bottom of the nose. The means comprises essentially a member which responds to a very light force and can be lifted by the incoming thread as the latter

2

rides up the hook. As the thread moves to a position in front of the hook the member returns to its normal position, and in doing so traps the thread. The member may be a bristle of nylon, or a resilient wire of small diameter clamped or otherwise secured to the shuttle feeler, or it may be rigid and pivoted on the shuttle feeler in such position that it can be swung upwardly by the thread as the latter is pushed upwardly along the hook.

In either form of retaining member it is desirable that it be constructed so as to permit ready attachment to shuttle position detectors now in use, and with this thought in mind it is a further object of the invention to provide a simple form of clamp carrying the retaining member and capable of being attached to the shuttle detector in such position as to locate the thread trapping member correctly with respect to the hook.

With these and other objects in view which will appear as the description proceeds, the invention resides in the combination and arrangement of parts hereinafter described and set forth.

In the accompanying drawings, wherein two forms of the invention are set forth,

Fig. 1 is a side elevation of a multicolor weft replenishing mechanism having the preferred form of the invention applied thereto, the lay and part of the loom frame being shown in cross section,

Fig. 2 is an enlarged side elevation of a part of the structure shown in Fig. 1 showing the thread retainer in full lines in its normal position and in dotted lines in the position to which it is moved by the incoming thread as the latter moves up the hook and is about to enter the trapping zone,

Fig. 3 is a horizontal section on line 3—3, Fig. 2,

Fig. 4 is a vertical section on line 4—4, Fig. 2,

Fig. 5 is a diagrammatic plan view showing the relation of the invention with respect to the thread of the incoming bobbin and associated parts, and

Fig. 6 shows a modified form of the invention employing a rigid member pivoted to the shuttle position detector and shown in two different positions.

Referring particularly to Fig. 1, the loom frame 1 supports the reserve bobbin magazine M which includes in its construction a transfferer arm 2 having a latch 3 pivoted thereto. The lay L is provided with a bunter 4 for engagement with the latch on transferring beats of the loom for the purpose of effecting rocking of the trans-

ferrer arm 2 in a counter-clockwise direction as viewed in Fig. 1, to move a reserve bobbin B from the magazine into the depleted shuttle S. The lay is provided with a shuttle box 5 formed with a forwardly facing thread placer or hook member 6.

The magazine is provided with a stationary stud 7 on which is pivoted a shuttle position detector 8 under control of a rod 9 operatively connected to a top or preventer shaft 10 of the magazine. The lower end of the shuttle position detector is formed with a rearwardly extending nose or head N provided with cutter mechanism designated generally at C. A rod 11 is connected at its lower end to a cutter blade 12 and at its upper end to a guide 13. A clamp plate 14 on nose N cooperates with blade 12 to hold the thread OT of the outgoing bobbin. The shuttle position detector and cutter mechanism of themselves are old and operate in the usual manner, and may be made as shown for instance in Patent No. 2,326,862.

Ordinarily the shuttle detector 8 will be in the position shown in Fig. 1 with its nose or head N in a forward position where it will not strike the shuttle S when the latter is in the box 5 and the lay moves toward front center position. When a bobbin transfer operation is called shaft 10 rocks to move the nose N rearwardly and the latch 3 is lifted into the path of the lay bunter 4. At the same time cutter blade 12 drops to its open position by action of rod 11.

During a normal bobbin transfer thread OT of the outgoing bobbin will pass to a position above blade 12, and as the lay approaches front center the rear or left part as viewed in Fig. 1 of the nose N will strike some part of the lay, such as that designated at 15, and be moved forwardly to reset the shaft 10. During forward motion of nose N blade 12 rises to cut thread OT and together with plate 14 clamps that part of the thread extending to the selvage.

As shown in Fig. 6 the loom is provided with the thread holder H which may be of any approved form to hold the thread IT of the incoming bobbin B as the latter is transferred into shuttle S. As the lay beats up on the beat of the loom next following replenishment the hook 6 on the lay will engage the thread IT and move it forwardly up the rear surface 20 of an upwardly and forwardly extending hook 21 on the nose N. The thread will pass to a position in front of the hook 21 and should fall against the top 22 of the nose and remain in this position, but under some conditions of weaving the thread is likely to whip out of this position and move to a position rearward of the hook and downwardly into the path of the shuttle where it may also become entangled with the clamped thread OT. Several picks after the bobbin transfer a temple cutter T will sever both threads, after which they may be removed.

All of the matter thus far described may be of the usual form and operate in the ordinary manner.

In order that provision may be made for trapping the thread in front of the hook 21 a yieldable member is provided which can be moved from its normal position by the thread as the latter is moved up hook surface 20 by hook 6 and then return to normal position to trap the thread.

In the preferred form of the invention an inherently resilient thread trapping member is employed, such as is shown in Figs. 2-4. A clip 25 preferably made of a single piece of thin sheet

metal is shaped as shown in Fig. 3 and is clamped to the shank 26 of the shuttle position detector 8 by means of a bolt 27. Secured to one side 28 of the clamp is a thin resilient member 29 which as shown in Fig. 2 is normally disposed below the top of the hook 21. As the thread IT is moved up the hook surface 20 by lay carried hook 6 it will enter a bight 30 formed by the member 29 and surface 20, and as the thread continues to move forwardly along hook 21 it will deflect the member 29 upwardly to the dotted line position shown in Fig. 2 and then pass to a position in front of the hook, whereupon the member 29 will return to the full line position shown in Fig. 2 due to its inherent resilience. The thread will then be trapped in zone Z located below member 29 and above the nose top surface 22, and in front of the hook 20 and rearward of the shank 26. The thread IT will be held in this zone against accidental displacement while waiting cutting at the selvage by the temple cutter T.

The thread trapping member 29 may be either a bristle made of some material such as nylon, or it may be a thin resilient metallic wire. The hook normally tapers upwardly as shown in Fig. 4 and will have right and left inclined sides 35 and 36. The member 29 will ordinarily engage one or the other of these inclined surfaces, engagement with the surface 35 being shown in Fig. 4. As the bristle or wire is lifted from the full line to the dotted line position shown in Fig. 2 it will tend to move away from the surface 35 and thereby facilitate entry of the thread IT into the trapping zone Z.

The modified form of the invention shown in Fig. 5 comprises a lightweight rigid retainer member 40 which has an eyelet 41 in the upper end thereof pivoted on one of the screws 42 which holds the ordinary leaf spring 43 against the clamp plate 14. The lower end of member 40 is curled forwardly as at 44 and rests on the upper end of the hook 21 and forms with the latter a thread bight 45. The pivot screw 42 is forward of the front end of hook 21 and as the thread IT is moved up the surface 20 it will enter bight 45 and engage the under side of the curved end 44 of the member 40 and lift the latter from the full line to the dotted line position shown in Fig. 5 and will then move into a zone Z1 located above the nose top surface 22 and forward of the hook 21 and member 40 and rearward of shank 26. When in this zone Z1 the thread will be held against accidental displacement, but should it happen to move rearwardly above hook 21 it will in all likelihood be trapped by the curved end or hook 44 at the bottom of the end 40 and be prevented from being moved permanently out of zone Z1.

From the foregoing it will be seen that the invention sets forth simple means to trap a thread in front of the hook 21 of a shuttle position detector. In the preferred form of the invention the trapping member may be a bristle or wire, while in the modified form the trapping member may be rigid and move about a pivot so located with respect to the hook 21 that it can be lifted slightly by the thread as the latter moves into zone Z1. As shown in Figs. 2 and 3, for instance, the thread trapping member 29 may be mounted on a small clip or holder which is readily attachable to the shank 26 of the shuttle position detector.

Having thus described the invention it will be seen that changes and modifications of the foregoing specific disclosure may be made without

departing from the spirit and scope of the invention.

What is claimed as new is:

1. In thread control mechanism for a weft replenishing loom having a thread extending from the cloth selvage to a thread holder, a lay having a thread placer for engagement with said thread as the lay moves forwardly, a shuttle position detector, an upwardly and forwardly extending thread hook on the shuttle detector, and a thread trapping member on the shuttle detector yieldable upwardly and when in normal position forming a thread bight with said hook, said placer on a forward beat of the lay moving the thread into said bight and upwardly along said hook to a position forward of the latter and causing the thread to effect upward movement of said trapping member from the normal position thereof, said trapping member subsequently moving downwardly to the normal position thereof to trap the thread forwardly of said hook.

2. In thread control mechanism for a weft replenishing loom having a thread placer on a lay to move a thread connected to the cloth selvage in a forward direction on the beat-up of the lay subsequent to a weft replenishing operation, a hook having an upwardly and forwardly extending surface, means mounting the hook in the path of the thread as the latter is moved forwardly by said placer, and a thread trapping member on said means normally positioned to form a thread trapping zone with the hook and means movable upwardly relatively to said hook and when in the normal position thereof forming with the hook a bight to receive the thread, the lay when moving forwardly causing said placer to move the thread into said bight and against the thread trapping member to raise the latter and move the thread into said zone, said trapping member thereupon returning to the normal position thereof to trap the thread in said zone.

3. In thread control mechanism for a weft replenishing loom having a thread placer on a lay to move a thread connected to the cloth selvage in a forward direction on the beat-up of the lay subsequent to a weft replenishing operation, a shuttle position detector having a shank and a rearwardly extending nose on the shank, an upwardly and forwardly extending hook projecting upwardly from the nose, and a thread trapping member effective when in normal position to define a trapping zone with the hook, nose and shank, the thread when moved forwardly by said placer engaging the trapping member to lift the latter and pass below the same over said hook into the trapping zone, said trapping member thereupon returning to normal position to confine the thread within said zone.

4. In thread control mechanism for a weft replenishing loom having a thread placer on a lay to move a thread connected to the cloth selvage in a forward direction on the beat-up of the lay subsequent to a weft replenishing operation, a shuttle position detector formed with a rearwardly extending nose, an upwardly and forwardly extending hook projecting upwardly from the nose, a clamp removably secured to the shuttle detector, and a thread trapping member supported by the clamp and movable upwardly relatively to said nose and when in the normal position thereof forming a thread receiving bight with said hook, the thread placer moving the thread into said bight and over the hook to a position in front of the latter and causing the

thread to effect movement of the trapping member from the normal position thereof, said trapping member thereafter returning to the normal position to trap said thread forward of the hook.

5. In thread control mechanism for a weft replenishing loom having a thread placer effective on the beat-up of the lay subsequent to a weft replenishing operation to move forwardly a thread connected to the selvage, a shuttle position detector formed with a rearwardly extending nose, an upwardly and forwardly extending hook projecting upwardly from the nose, and an inherently resilient thread trapping member carried by the shuttle detector and when in normal position extending along the hook at a point below the top of the latter and forming with the hook a bight to receive the thread as the latter is moved forwardly by said placer, the placer causing the thread to bend said trapping member upwardly so that the placer can move the thread over the hook to a position in front of said hook, said member thereupon due to the resilience thereof returning to the normal position thereof to trap the thread in front of said hook.

25 6. In thread control mechanism for a weft replenishing loom having a thread placer on a lay to move a thread connected to the cloth selvage in a forward direction on the beat-up of the lay subsequent to a weft replenishing operation, a shuttle position detector having a shank and a rearwardly extending nose at the bottom of the shank, an upwardly and forwardly extending thread hook projecting upwardly from said nose, and a thread trapping member pivoted to the shank forward of the hook and when in the normal position thereof forming a thread bight with the hook, the thread being moved by said placer up along the thread hook into engagement with the trapping member to lift the latter and then to a position forward of the hook, said trapping member thereupon returning to the normal position thereof to trap the thread.

7. In a shuttle position detector for a weft replenishing loom, said detector comprising a shank, a rearwardly extending nose on the shank, an upwardly and forwardly extending thread hook projecting upwardly from the nose, and a thread trapping member movable relatively to the shuttle position detector and when in normal position forming a thread receiving bight with said hook, said trapping member being movable upwardly by a thread passing from the bight over the hook to a position forward of the latter and thereafter returning to the normal position thereof.

8. In a shuttle position detector for a weft replenishing loom comprising a shank and a nose extending rearwardly from the lower end of the shank, an upwardly and forwardly extending

60 thread hook projecting upwardly from the nose, a clamp releasably secured to the shank, and a thread trapping member supported by the clamp effective when in normal position to form a thread bight with said hook, said trapping member being movable upwardly from said nose to a position to permit passage of a thread from said bight over said hook to a position forward of said latter and thereafter returning to the normal position thereof.

65 9. In a shuttle position detector for a weft replenishing loom comprising a shank and a nose extending rearwardly from the lower end of the shank, an upwardly and forwardly extending thread hook projecting upwardly from the nose, a clamp releasably secured to the shank, and an

Inherently resilient thread trapping member supported by said clamp normally below the top of the hook forming a thread bight with said hook but deflectable upwardly to permit a thread to pass from the bight over the hook to a position forward of the hook.

10. In a shuttle position detector for a weft replenishing loom comprising a shank and a nose extending rearwardly from the lower end of the shank, an upwardly and forwardly extending thread hook projecting upwardly from the nose, said hook having a side surface inclined upwardly and laterally of said nose, and an inherently resilient thread trapping member supported by the shuttle detector normally engaging said inclined surface below the top of the hook and forming a thread bight with the hook, said trapping member being deflectable upwardly from

the nose to a position spaced from said inclined surface to facilitate passage of a thread from said bight over the hook to a position forward of the hook.

5 11. In a shuttle position detector for a weft replenishing loom, a rearwardly extending nose, thread cutter and clamp mechanism to clamp a thread at the bottom of the nose, an upwardly and forwardly extending hook projecting upwardly from the top of the nose, and a thread trap member cooperating with the hook and top of the nose to trap a second thread forward of the hook and keep said second thread spaced from the first thread clamped at the bottom of said nose.
